UNITED STATES PATENT OFFICE

FREDERICK WALK, OF PHILADELPHIA, PENNSYLVANIA.

IMPROVEMENT IN HORSESHOE-CALKS.

Specification forming part of Letters Patent No. 179,827, dated July 11, 1876; application filed January 10, 1876.

To all whom it may concern:

Be it known that I, Dr. FREDERICK WALK, of Philadelphia, Pennsylvania, have invented an Improved Horseshoe, of which the following is a specification:

The object of my invention is to so construct a horseshoe as to prevent the undue wearing of the body of the shoe, and to provide for the ready removal and replacing of the toe and heel-calks, and this object I attain in the manner which I will now proceed to describe, reference being had to the accompanying drawing, in which—

Figure 1 is a vertical section of my improved horseshoe, with one of the heel-calks also in section; Fig. 2, a transverse section on the line 1 2; Fig. 3, a perspective view of the toe of the shoe with the parts detached from each other; and Fig. 4, an inverted perspective view of the detachable toe-plate and calk.

A is the body of the shoe, which is recessed on the under side at the front *a* for the reception of the projection *b* on a detachable plate, B, having flanges *d* *d*, by means of which it can be secured to the body A by bolts *e*. The projection *b* is slotted for the reception of a tongue, *f*, on the toe-calk D, which is secured in position in the present instance by means of a key, *g*, driven through an opening, *h*, in the tongue *f*, and bearing against the inner edges of the plate B, as shown in Fig. 1.

Lateral steadiness of the toe-calk is insured partly by the curve of the front of the shoe, but more especially by a projection, *i*, on the calk, this projection fitting into a recess formed in the plate B, and a lip, *m*, on the calk overlapping and protecting the edges of this recess. The front of the calk D is carried upward beyond the top of the shoe and forms a hoof-guard, E.

The heel-calk which I prefer to use in connection with the above-described toe-calk, is shown in Figs. 1 and 2, and consists of a block, F, and guard or calk G. The block F has a stem, *n*, adapted to a vertical slot near the end of the body A of the shoe, and retained in position therein by a transverse pin, *o*, and

the lower portion of the block is grooved for the reception of ribs on the upper edge of the guard or calk G, which is closed at the front, so as to protect the front edge of the block F, and is secured to the latter by means of a transverse key, *p*.

The above-described devices form a means of providing a horseshoe with calks which can be readily attached or detached, the only extra labor incurred by the blacksmith in preparing the shoe for their reception being the formation of the recess *a* at the front and a slot in each of the rear ends of the shoe.

The detachable toe plate and calk and heel block and guard, which I propose to make of cast-iron or steel, can be produced at a cost of but a few cents each, and, when the plate B and block F are once applied, the toe and heel calks can be removed and replaced, and the horse either rough-shod or smooth-shod in a few moments, and without the aid of any special tools.

Owing to the construction of the toe and heel calks the plate B and block F are amply protected, and are not liable to fracture from sudden blows or shocks.

Different modes of securing the toe-calk to the plate B, and of attaching the latter to the shoe, may be substituted for those shown and described, as will be evident without further description.

I claim as my invention—

1. The combination of the body A of the shoe and its recess *a* with the detachable toe-plate B and its slotted projection *b*, and the toe-calk D and its tongue *f*, adapted to and secured within the slotted projection *b*, all substantially as set forth.

2. The combination of the shoe and its slotted and recessed plate B with the toe-calk D, its tongue *f*, and projection *i*, as set forth.

In testimony whereof I have signed my name to this specification before two subscribing witnesses.

FREDERICK WALK.
